CLAMPING DEVICE

Harry H. Merwin, Rutherford, N. J., assignor to
Western Electric Company, Incorporated, New
York, N. Y., a corporation of New York

Application May 8, 1942, Serial No. 442,222

18 Claims. (Cl. 57—69)

This invention relates to clamping devices, and more particularly to self-locking reel clamping devices.

Reels, particularly those of the take-up type, used in various stranding machines for taking up the finished product of such machines, are rotated about their own axis and, in some instances, they are rotated about an axis at right angles to their own axis. During such times it is important to condition the mechanism supporting the reel against loosening during the times the reel is rotated.

An object of the invention is to provide a clamping device which is simple in structure, easily actuatable and positive in its locking effect against accidental releasing of the part it is clamping.

With this and other objects in view, the invention comprises a clamping device having a threadedly supported clamping element mounted for movement relative to a fixed position clamping member to clamp an article therebetween and self-locking means adapted to allow free movement of the element in a direction toward the clamping member to clamp an article and to prevent movement of the element in the reverse direction, cam means being provided to release the locking means for movement of the element in the reverse direction to release the article.

Other objects and advantages will be apparent from the following detailed description when considered in conjunction with the accompanying drawings, wherein

Fig. 1 is a front elevational view of the take-up end of a stranding machine illustrating the invention;

Fig. 2 is a fragmentary vertical sectional view of a portion of the machine embodying the invention;

Fig. 3 is a fragmentary sectional view taken along an irregular path, represented by the section line 3—3 of Fig. 2, to illustrate the relative positions of the different parts in this structure;

Fig. 4 is an enlarged fragmentary side elevational view of a portion of the clamping device, portions thereof being broken away to show the inner structures thereof;

Fig. 5 is a fragmentary top plan view taken along the line 5—5 of Fig. 2;

Fig. 6 is a fragmentary sectional view taken along the line 6—6 of Fig. 4, and

Fig. 7 is a fragmentary sectional view taken along the line 7—7 of Fig. 3.

Referring now to the drawings, attention is

first directed to Fig. 1, which illustrates a take-up unit, indicated generally at 10, of a stranding machine which has been selected to illustrate the invention. The unit 10 includes a flier frame 11 having a hollow shaft mounted in bearings 14 supported on an upright frame 15, the opposite end of the flier frame 11 being annular, as at 16, and supported for rotation between sets of rollers 17. The flier 10 is driven by a motor 18, through a sprocket and chain connection 19, with the shaft 12 of the flier, this driving means also driving a sprocket and chain connection 20 which drives a shaft 21. A shaft 22, rotatably supported by the frame 11, supports, at its inner end, a cone center 23 receivable in an end of a hub 24 of a take-up reel 25. Suitable means, such as a pin 27, fixed for rotation with the shaft 22 may provide a positive connection between the reel 25 and the shaft. A chain of gears 28, 29, 30 and 31 operatively connects the shaft 21 with the shaft 22, to cause rotation of the reel 25 counterclockwise, looking downwardly on Fig. 1, during rotation of the frame 11, to rotate the reel about an axis at right angles to its axis. During this rotation of the reel a strand or cable 32 is wound thereon and distributed through the aid of a distributing unit 33. The structure thus described has been selected to illustrate the importance of the clamping device. The clamping device is indicated generally at 35 and functions in cooperation with the center 23 to clamp the reel in place in the frame 11.

Attention is now directed to Figs. 2 to 7, inclusive. Referring first to Fig. 2, the clamping device includes a center member 36 receivable in the hub 24 of the reel 25 at the end opposite the center 23. The center 36 is mounted upon the end of a shaft 37 which is supported by bearing 38 mounted in a threaded element 40. The element 40 is threadedly disposed in an internally threaded sleeve 41, the latter being disposed in an aperture 42 of the adjacent portion of the frame 11 and rigidly secured in place by the aid of screws 43, only one of which is shown in Fig. 2. The element 40 has a reduced portion 44 at the upper end of the threaded portion thereof which extends upwardly to a plane or surface 45, where a further reduced or integral shank portion 46 is disposed axially of both the element 40 and the threaded portion of the element.

The shank portion 46 has a hand wheel 48 mounted for free rotation thereon and held against displacement by a nut 49 and a washer 50, the nut being threadedly disposed on the threaded end of the shank 46. The hand wheel

48 has an annular hub portion 51 disposed concentric with the shank 46 and free to rotate thereon. An annular cam member 52 is disposed concentric with the hub 51 and is rigidly secured to the hand wheel 48 by the aid of screws 53. At spaced positions at the under portion of the cam 52, enlarged integral portions 55 are disposed, like ends of these portions having vertical abutting surfaces 56, the opposing ends having diagonal cam surfaces 57. The portions 55 of the cam 52 are receivable in recesses 58 of a locking element 59, the recesses being disposed at spaced positions about the upper portion of the element similar to the spacing of the portions of the cam. The element 59 is annular in general contour, centrally apertured to receive the shank portion 46 and rigidly mounted on the surface 45 of the portion 44 by screws 59'. The recesses 58 in the upper portion thereof are longer than the length of the portions 55 of the cam 52, so as to allow relative rotation of the cam and the element for limited distances. The ends of each of the recesses 58 have vertical surfaces 60, certain of them being positioned for abutting engagement with the surfaces 56 of its respective portion 55, the others being positioned for abutting engagement with a surface 61 of the cam 52 adjacent the cam surface 57. Through the surfaces 56 and 61 and their respective surfaces 60, a positive engagement is formed between the cam 52 and the locking element 59. Apertures 62 are provided in the locking element 59 at spaced positions adjacent the recesses 58. Ball members 63 are disposed in the apertures 62 for free movement therein, the ball members being under the control of the respective portions of the cam 52 and the cam surfaces 57 thereof, for a purpose hereinafter described.

Attention is now directed to the circular arrangement of teeth 64 formed in the under surface of the locking element 59 and also a recess 65 in the element. A similar locking element 68, annular in general contour and disposed concentric with the portion 44 of the element 40, has a circular arrangement of teeth 69 adapted for interengagement with the teeth 64 of the locking element 59. The element 68 is also recessed as at 70, a metallic ring 71 being disposed in this recess beneath the path of the ball members 63. An annular recess 72 of a supporting member 73 is of a contour to receive the element 68, the member being fixedly held in place by screws 74. The supporting member 73 is centrally apertured for free movement on the portion 44, the supporting member being of the contour shown in Fig. 5, with ends extending beyond the element 40 to support control pins 75 (Figs. 2 and 5). The pins 75, being supported at diametrically opposed positions relative to the element 40, project downwardly into apertures 76 of the adjacent portion of the frame 11, springs 77 being disposed concentric therewith between the upper surface of the frame and the under surface of the support 73 to normally urge the support upwardly with the locking element 68 to move the latter into registration with the locking element 59, maintaining normal interengagement of their teeth 69 and 64, respectively.

Considering now the operation of the device, let it be assumed that an empty reel 25 is to be mounted between and on the cone centers 23 and 36. At this time the cone center 36 will be spaced a sufficient distance away from the cone center 23 for the insertion of an empty reel 25 therebetween. The most convenient position of the

frame 11 for the mounting of the reel in place is as illustrated in Fig. 1, with the cone center 23 below and the device 35 above. At this time the empty reel may be located on the cone center 5 23 and by rotating the hand wheel 48 clockwise (Fig. 5), the cam 52 will be rotated therewith.

During the rotation of the hand wheel and the cam clockwise, the surfaces 56 of the cam portions 55 will abut their respective surfaces 60 of the locking element 59, causing rotation of the locking element 59 relative to a locking element 68. Relative rotation of the locking elements, that is the locking element 59 relative to the locking element 68, is permitted due to the formation of the 15 teeth of the elements, the locking element 68 being moved downwardly against the force of the springs 77. It is, therefore, apparent that the locking element 68 will not interfere with the rotation of the threaded element 40 in a clockwise direction to move the cone center 36 downwardly, that is toward the cone center 23, until the former has been positioned in the adjacent end of the hub 24 of the reel. When the reel is clamped in place it is ready to receive the 20 strand or cable 32, after which the stranding machine may be set in motion through the operation of the motor 18 driving the flier 10, to rotate the reel about an axis at right angles to its own axis and also, through the driving means, 25 connecting the motor with the cone center 23, to rotate the reel about its own axis to take up the cable thereon.

With the structure of the clamping device, the cone center 36 thereof, or the element which engages the article to be clamped, may be moved into place by clockwise rotation of the hand wheel 48. Once the cone center is in place, it is automatically locked against displacement as soon as the operator releases the hand wheel.

40 The automatic locking is ever present through the associated locking elements 59 and 68, the latter being held against rotation by the control pins 75 and normally urged into engagement with the former locking element through the force of the 45 springs 77. Furthermore, the cone center, the part which functions in clamping the article, namely the reel, is supported for free rotation without affecting the clamping means. The rotation of the clamping device about an axis at right angles to its own axis, increases the holding force of the locking means due to the effect of centrifugal force being added to the force of the springs 77 to urge the supporting member 73 together with the locking element 68 outwardly 50 to maintain intimate engagement of the teeth of the locking element 68 with those of the locking element 59.

When the reel is filled and the stranding machine is again stopped at the position shown in 60 Fig. 1, the operator may remove the reel by rotating the hand wheel 48 in a counterclockwise direction. During the first portion of this movement, the cam 52 is moved to cause its portions 55, particularly the cam surfaces 57, to move 65 into engagement with the ball members 63, moving the ball members inwardly to the position shown in Figs. 4 and 6. During this movement of the ball members, inward pressure is applied through the ball members to the annular member 71, to move it with the locking element 68 inwardly, which in this instance is downwardly, from the position shown in Fig. 7 to the position shown in Figs. 4 and 6, moving the locking element 68 out of engagement with the element 59. 70 At this time, when the surfaces 61 of the cam

52 engage the adjacent surfaces 60 of the element 59, the mechanism is then free for continued counterclockwise movement of the hand wheel, which movement imparts movement of the threaded element 40 in the same direction. Due to the threaded engagement of the element 40 with the sleeve 41, the counterclockwise movement of the former will move the cone center 36 out of the hub 24 and free the reel 25 for removal of the reel from the cone center 23.

It is apparent that the clamping device may be freely actuated in either direction to clamp an article or release an article by the rotation of the hand wheel in either clockwise or counterclockwise directions, no additional effort being required of the operator to lock or unlock the device. The device is self-locking once the article is clamped in place, thus relieving the operator of the responsibility of locking the structure in clamped position and eliminating any possibility of the clamping means becoming loose while in service. Furthermore, the structure of the clamp is not affected by centrifugal force to loosen the clamping means during operation of the machine but utilizes this force to increase the locking effort of the interengaging parts.

Although specific improvements of the invention have been shown and described, it will be understood that they are but illustrative and that various modifications may be made therein without departing from the scope and spirit of this invention as defined by the appended claims.

What is claimed is:

1. A clamping device comprising a threadedly supported clamping unit, a rotatable actuator, means under the control of the actuator to move the unit into a position to clamp an article when the actuator is rotated in one direction, and means to lock the unit against rotation in a reverse direction to maintain the unit in the clamping position.

2. A clamping device comprising a threadedly supported clamping unit, a rotatable actuator, means under the control of the actuator to move the unit into a position to clamp an article when the actuator is rotated in one direction, means to lock the unit against rotation in a reverse direction to maintain the unit in the clamping position, and means actuatable by the rotation of the actuator in the reverse direction to release the locking means.

3. A clamping device comprising a threadedly supported clamping unit, a rotatable actuator, means under the control of the actuator to move the unit into a position to clamp an article when the actuator is rotated in one direction, means to lock the unit against rotation in a reverse direction to maintain the unit in the clamping position, and means actuatable by the rotation of the actuator in the reverse direction to release the locking means and cause movement of the unit free of the article.

4. A clamping device comprising a threadedly supported clamping unit, a companion clamping member disposed at a fixed position relative to the clamping unit, a rotatable actuator, means under the control of the actuator to move the unit into a position relative to the clamping member to clamp an article therebetween when the actuator is rotated in one direction, and means to lock the unit against rotation in a reverse direction to maintain the unit in the clamping position.

5. A clamping device comprising a threadedly supported clamping unit, a companion clamping

member disposed at a fixed position relative to the clamping unit, a rotatable actuator, means under the control of the actuator to move the unit into a position relative to the clamping member to clamp an article therebetween when the actuator is rotated in one direction, means to lock the unit against rotation in a reverse direction to maintain the unit in the clamping position, and means actuatable by the rotation of the actuator in the reverse direction to release the locking means.

6. A clamping device comprising a threadedly supported clamping unit, a companion clamping member disposed at a fixed position relative to the clamping unit, a rotatable actuator, means under the control of the actuator to move the unit into a position relative to the clamping member to clamp an article therebetween when the actuator is rotated in one direction, means to lock the unit against rotation in a reverse direction to maintain the unit in the clamping position, and means actuatable by the rotation of the actuator in the reverse direction to release the locking means and cause movement of the unit free of the article.

7. A clamping device comprising a threaded clamping unit, a threaded support therefor, a companion clamping member disposed at a fixed position relative to the clamping unit, a rotatable actuator, means under the control of the actuator to move the unit into a position relative to the clamping member to clamp an article therebetween when the actuator is rotated in one direction, and means to lock the unit against rotation in a reverse direction to maintain the unit in the clamping position.

8. A clamping device comprising a threaded clamping unit, a threaded support therefor, a companion clamping member disposed at a fixed position relative to the clamping unit, a rotatable actuator, means under the control of the actuator to move the unit into a position relative to the clamping member to clamp an article therebetween when the actuator is rotated in one direction, a locking unit adapted to lock the clamping unit against movement in the reverse direction to maintain the clamping unit in the clamping position, and means actuatable by the actuator to release the locking unit.

9. A clamping device comprising a threaded clamping unit, a threaded support therefor, a companion clamping member disposed at a fixed position relative to the clamping unit, a rotatable actuator, means under the control of the actuator to move the unit into a position relative to the clamping member to clamp an article therebetween when the actuator is rotated in one direction, a locking unit adapted to lock the clamping unit against movement in the reverse direction to maintain the clamping unit in the clamping position, and means actuatable by rotation of the actuator in the reverse direction to release the locking unit.

10. A clamping device comprising a threaded clamping unit, a threaded support therefor, a companion clamping member disposed at a fixed position relative to the clamping unit, a rotatable actuator, means under the control of the actuator to move the unit into a position relative to the clamping member to clamp an article therebetween when the actuator is rotated in one direction, a locking unit adapted to lock the clamping unit against movement in the reverse direction to maintain the clamping unit in the clamping position, and means actuatable by rotation of the

actuator in the reverse direction to release the locking unit and cause movement of the clamping unit to free the article.

11. A clamping device comprising a threadedly supported clamping unit, a rotatable actuator, means under the control of the actuator to move the unit into a position to clamp an article when the actuator is rotated in one direction, means to lock the unit against rotation in a reverse direction to maintain the unit in the clamping position, and cam controlled means actuatable by the rotation of the actuator in the reverse direction to release the locking means.

12. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit, relative to the member to clamp an article therebetween, and means to apply a locking force to the clamping unit to lock it in the clamping position.

13. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit relative to the member to clamp an article therebetween, and means affected by centrifugal force during rotation of the rotatable unit to lock the clamping unit in the clamping position.

14. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit relative to the member to clamp an article therebetween, means affected by centrifugal force during rotation of the rotatable unit to lock the clamping unit in the clamping position, and means to release the locking means.

15. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit relative to the member to clamp an article therebetween, a locking mem-

ber, means adapted for interengagement with the locking member secured to the clamping unit, and means to apply a force to the locking member to cause interengagement thereof with the said means secured to the clamping unit.

16. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit relative to the member to clamp an article therebetween, a locking member, means adapted for interengagement with the locking member secured to the clamping unit, and means affected by centrifugal force during rotation of the rotatable unit to cause interengagement of the locking member with the said means secured to the clamping unit to lock it against movement.

17. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit relative to the member to clamp an article therebetween, a locking member, a connecting member adapted for interengagement with the locking member secured to the clamping unit, and a force applying means aided by centrifugal force on the locking member during rotation of the unit to force the locking member into interengagement with the connecting member.

18. The combination with a rotatable unit and means to cause rotation of the unit about an axis, of a clamping device comprising a clamping unit threadedly supported in the rotatable unit for movement in a direction transverse the said axis, a companion clamping member mounted at a fixed position in the rotatable unit relative to the clamping unit, means to move the clamping unit relative to the member to clamp an article therebetween, a locking member, a connecting member adapted for interengagement with the locking member secured to the clamping unit, a force applying means aided by centrifugal force on the locking member during rotation of the rotatable unit to force the locking member into interengagement with the connecting member, and means to move the locking member free of the connecting member to condition the clamping unit for movement to free the article.

HARRY H. MERWIN.
